ALPHABET PUZZLE OR THE LIKE

George J. Paulus, 14 Midway St.,
San Francisco, Calif. 94133

Filed May 25, 1967, Ser. No. 7,261

Term of patent 14 years

(Cl. D34—15)

FIG. 1 is a top plan view of an alphabet puzzle or the like showing my new design, the shading merely being for the purpose of distinguishing the letters in the puzzle;

FIG. 2 is an edge view thereof;

FIG. 3 is a plan view of one of the clusters of letters illustrating the nesting characteristics thereof; and

FIG. 4 is a top plan view of the letters of FIG. 1 as they appear disposed in side-by-side relation in their alphabetical order.

The dominant feature of the design is the cluster-forming characteristics of the letters.

I claim:

The ornamental design for an alphabet puzzle or the like, substantially as shown and described.
